UNITED STATES PATENT OFFICE.

LULU H. MILLER, OF BROOKLYN, NEW YORK.

APPARATUS FOR FOLDING GAUZE FOR SURGICAL DRESSINGS, &c.

1,268,596.

Specification of Letters Patent. Patented June 4, 1918.

Application filed April 5, 1918. Serial No. 226,916.

To all whom it may concern:

Be it known that I, LULU H. MILLER, a citizen of the United States, and a resident of the borough of Brooklyn, county of 5 Kings, city and State of New York, have invented certain new and useful Improvements in Apparatus for Folding Gauze for Surgical Dressings, &c., of which the following is a specification.

10 My invention, while applicable to various other uses, is designed more especially to afford simple, cheap, but effective means whereby gauze for surgical dressings may be conveniently and quickly unwound from the 15 commercial bolt and folded evenly into superposed layers which may be cut into suitable lengths with accuracy and without waste, as hereinafter more fully set forth.

The invention consists in the specific combination and arrangement of parts described and claimed,—distinctive features being the means for prescribing the length of fold; the feed of the gauze from the bolt to the 25 folding table; the adjustment of the length of fold, and the holding of the folds taut, etc.

In the accompanying drawings,

Figure 1, is a plan of a gauze manipulating and cutting table or board embodying 30 the essential features of my invention,—the gauze being broken away in part for clearness of illustration;

Fig. 2, is an elevation of the parts shown in Fig. 1;

Fig. 3, is a sectional detail showing an elevation of one extremity of one of the pin racks;

Fig. 4, is a sectional detail showing one extremity of the spreader frame.

40 The commercial bolt of gauze is flat, and either of full width, or folded double around a flat card board. When the full width bolt is to be manipulated the rotatable spindle a , is dispensed with and the full width bolt 45 laid on the table t , a suitable distance behind or to the right of the guide bar g , which is mounted on the under side of the cross bar c , supported by the end standards s , s , the lower ends of which are provided with screw 50 or equivalent clamps s' , s' . The guide bar g , is preferably a roller the ends of which rest in sockets c' , (one of which is shown in Fig. 4) on the under side of the cross bar c . The roller facilitates the feeding of the gauze to 55 and between the pin racks r , and lessens frictional resistance to such feed.

When the bolt is of the half width type, the card board core is removed, the spindle a , inserted through the bolt in lieu thereof, and the spindle a , mounted upon and between bifurcated ends of the standards a' , a' , which are clamped to the edges of the table, so as to be readily removed therefrom when not desired for immediate use. When the folded bolt is thus mounted it is opened 60 up to full width before being first fed to and over the guide g , after which it will unfold itself as drawn over said guide g .

The pin racks r , r , are strips of wood or other suitable material of a length equal to 70 the width of the table t , and are formed at each extremity with a screw clamp r' , or equivalent, by means of which they may be readily adjusted along the length of the table t , the edges of which are formed with 75 coincident scales k , (see Fig. 1) so that the alinement of the racks r , transversely across the table may be readily and accurately attained,—the distance apart of the two racks r , being of course regulated according to the 80 lengths of folds desired.

The pins p , project upward vertically from the rack bars r , and are sufficiently close and numerous to insure a firm hold on the bights of the gauze fabric f , as folded 85 over from one rack and set of pins to the other. This action is illustrated in exaggerated form in Fig. 2, but illustrates the principle and function involved. The bights b , in the fabric f , are formed carefully and 90 gaged by the width of the rack bars r , so that accurate alinement is readily attained. This insures uniformity of width of dressing strips when the fabric is cut between the 95 rack bars, which cutting operation is performed when a suitable number of layers of the fabric f , are superposed one upon the other.

The cutting may be effected by any known or suitable means, as an electrically driven 100 cutter, shears, or the like as may be found most convenient or expedient,—and the folded fabric may be marked for the purpose of cutting by means of a ruler extended transversely across the folds and gaged in 105 position by means of the aforesaid scales k , k , at or adjacent to the edges of the table t .

The numerous pins p , hold the fabric taut and even; and the accuracy and uniformity of size of the bights b , insure uniformity of 110 width of the cut goods and eliminates waste of material.

The whole arrangement is very simple and inexpensive, and well adapted to the requirements of Red Cross work and necessities. The device is in extensive use in many 5 Red Cross auxiliaries; and it is the applicant's purpose to dedicate it to such use.

What I claim as my invention and desire to secure by Letters Patent is,

In gauze folding apparatus of the character designated, the combination of a sup-

porting table formed with coincident scales on opposite sides thereof, a guide roller mounted upon and above said table, and transverse pin racks adjustably mounted upon said table, for the purpose described. 15

LULU H. MILLER.
